UNITED STATES PATENT OFFICE.

ANDREW B. SEARLES, OF PROVIDENCE, RHODE ISLAND.

IMPROVED TABLE-CASTER.

Specification forming part of Letters Patent No. **88,911**, dated April 13, 1869.

To all whom it may concern:

Be it known that I, ANDREW B. SEARLES, of the city of Providence, in the county of Providence and State of Rhode Island, have invented a new and Improved Table-Caster; and I do hereby declare that the following is a full, clear, and exact description thereof, reference being had to the accompanying drawings, in which—

Figure 1 is a perspective view; Figs. 2, 3, and 4, detail views.

Similar letters of reference indicate like parts in all the drawings.

The object of my invention is to produce a light, ornamental, and cheap table-caster, which shall be very strong and durable.

It consists in making a caster of twisted wire, and so uniting the various parts and by bracing with ornaments that I am enabled to make a strong and beautiful article at a very moderate cost.

To enable others skilled in the art to make my improved caster, I will describe the construction of the same.

A A A represent two wires, which form the handle, braces, and legs. B B B are the rings which hold the bottles. C C C are ornaments, which brace the rings and legs. D is an ornament, which braces the handle.

The parts A A A, which form the handle,

braces, and legs, are first twisted up of wire of the desired length, and the two are then bent by any suitable mechanical device into the form as shown in Fig. 1, and secured by fine wire at d e.

The bottle-rings B B B are made of twisted wire and bent in circular shape. The rings are secured to the braces and the ornamental braces to the rings and legs and handle at e by fine wire or with narrow metal bands.

The ornamental braces C C C and D are made also of twisted wire, and bent into form and bound with fine twisted wires at e e e, &c., in Fig. 4.

The whole is then dipped in molten metal, and thereby soldered and tinned at one operation.

Having thus described my invention, I claim as a new and improved article of manufacture—

A table-caster constructed of twisted wire, consisting of the handles, braces, legs, and feet A, rings B, and ornamental braces C, bound together with fine wire, and constructed as and for the purposes described and specified.

ANDREW B. SEARLES.
